(57) **CLAIM**

The ornamental design for a log splitter table, as shown and described.

DESCRIPTION

FIG. 1 is a bottom perspective view showing the left side and front of a log splitter table showing my new design.

FIG. 2 is a front view thereof.

FIG. 2 is a right side view thereof.

FIG. 4 is a top view thereof.

FIG. 5 is a rear view thereof.

FIG. 6 is a bottom view thereof.

FIG. 7 is a left side view thereof.

FIG. 8 is a perspective view in one possible environment; and,

FIG. 9 is a left side view in one possible environment.

The broken-line showing of environmental structure in FIGS. 8 and 9 are for illustrative purposes only and forms no part of the claimed design.
